PAPER CLIP

Richard S. Kelly, Ridgefield Park, N. J.

Application September 22, 1934, Serial No. 745,038

1 Claim. (Cl. 24—261)

This invention relates to paper clips and the like and has for its object to provide a simple, novel and effective spring clip made of a single piece of spring wire and one that may be readily applied to a plurality of sheets of paper or similar articles for securing them together.

Various expedients have been resorted to, to increase the gripping power of paper clips, over those made of plain wire having a circular cross section. My improvements are directed to similar ends and comprise the employment of wire having a polygonal cross section and which wire is twisted so as to produce helical ribs, which are highly efficient in gripping the papers to which the clip is applied.

My improved clip may be of the usual form comprising a length of wire bent on itself to form closely adjacent portions nested one within the other on each side of the clip, well known in the stationery arts.

It is obvious that my improvements may be equally well applied to various other forms of clips. The present form is illustrative rather than definitive.

Referring to the drawing, Figure 1 shows a

front view of a clip embodying my improvements. Fig. 2 is an edge view of the same. Fig. 3 is a front view similar to that of Fig. 1, but to a larger scale to show more clearly my improvements. Figs. 4, 5, 6 and 7 include a series of enlarged cross sections of wire suitable for use in my improved clip. Other cross sections will be obvious to those skilled in the art.

I prefer a wire of square cross section and have so shown it in Figs. 1, 2 and 3. Said wire is twisted, as clearly shown in Fig. 3 so as to produce a plurality of helically disposed ribs 2 which I have found to be particularly efficient in gripping paper or other sheets to which the clip is applied.

I claim:

A paper clip comprising a section of wire, the opposite ends of which terminate in U-shaped portions, the intermediate portion of said wire being bent to U-shape so as to locate the said U-shaped portions in nested and operative relation with respect to each other, and the wire of said clip being of polygonal cross section twisted to provide a plurality of helical ribs.

RICHARD S. KELLY.
